UNITED STATES PATENT OFFICE

160,324

EXHAUST PIPE EXTENSION OR SIMILAR
ARTICLE FOR AN AUTOMOBILE

George C. Knight, Detroit, Mich., assignor to George C. Knight Company, Detroit, Mich., a corporation of Michigan

Application December 17, 1949, Serial No. 6,687

Term of patent 7 years

(Cl. D14—6)

To all whom it may concern:

Be it known that I, George C. Knight, a citizen of the United States, residing at Detroit 27, Wayne County, Michigan, have invented a new, original, and ornamental Design for an Exhaust Pipe Extension or Similar Article for an Automobile, of which the following is a specification, reference being had to the accompanying drawing, forming a part thereof.

Fig. 1 is a perspective view of an exhaust pipe extension or similar article for an automobile, embodying my invention.

Fig. 2 is a side elevational view thereof.

Fig. 3 is a plan view thereof.

I claim:

The ornamental design for an exhaust pipe extension or similar article for an automobile, substantially as shown.

GEORGE C. KNIGHT.
